HARDENING-MACHINE.

1,299,949.

Specification of Letters Patent.

Patented Apr. 8, 1919.

Application filed October 22, 1917. Serial No. 197,856.

To all whom it may concern:

Be it known that we, CHESTER C. JACKMAN and RAYMOND S. SQUIRE, citizens of the United States of America, residing at Springfield, in the county of Hampden and State of Massachusetts, have invented certain new and useful Improvements in Hardening-Machines, of which the following is a specification.

10 This invention relates to improvements in machines for automatically hardening steel articles, such as hack-saw blades, for example. The invention, furthermore, relates to improvements in machines of the type disclosed in our copending application Serial No. 148,250, filed February 12, 1917.

In such machines, articles, as hack-saw blades, are connected into continuous chain form and passed successively through a heating and a quenching means, the latter generally involving the use of oil. It is obviously desirable to subject the articles to the action of the quenching means as soon as possible after their exit from the heating means. To obtain this desirable result, the quenching and heating means are necessarily located adjacent one another, and, by reason of such proximity, much difficulty has been hitherto experienced from the ignition of the oil. A further source of difficulty is experienced from the splash of the oil used for quenching purposes against the incoming chain of red hot saws. If such oil first strikes a heated surface and is then deflected therefrom against the heated saws, ignition is liable to occur. The present invention is to be distinguished from others dealing with the prevention of the oil following back along the saw chain into the furnace, and it

40 is recognized that various means have been proposed to overcome this difficulty, as evidenced by the prior art. For example, various arrangements have been used to prevent the oil from following back along the saws into the furnaces, as shields and devices yieldingly forced against the articles. However effective such devices may be to prevent direct ignition of the oil by the furnace, they are not effective for the present purpose, for 50 they do not prevent the heating of the oil indirectly from the furnace nor the ignition of such heated oil as encounters the red hot saws in a splash or spray. The danger from

the ignition of even small quantities of oil lies in the possibility of communication with the main body of oil, and, where the quenching means consists of an oil bath, it will be apparent that a serious conflagration may result.

According to one feature of the invention, 60 the chain of articles is passed successively through a heating and a quenching means and a tank is associated with the latter to receive oil therefrom, which tank has a jacketed wall adjacent the exit of the heating means to receive a cooling medium, whereby the oil falling into said tank and against its walls may be cooled sufficiently to prevent its ignition by the incoming heated chain of articles. 70

According to another feature of the invention, the quenching means takes the form of a relatively large body of oil through which the heated articles travel in a straight line at a substantial distance below the surface to prevent "flashing" of the oil, and such oil as passes from the oil bath through the entrance orifice of the oil bath enters a tank interposed between the oil bath and the heating means and the wall of the tank adjacent the latter is cooled by the circulation of a suitable medium therein, so that such oil as enters the tank is cooled sufficiently to prevent its ignition by the incoming heated articles. 85

Other features of the invention will appear in the following description and in the illustrative embodiment of the invention in the accompanying drawings, in which—

Figure 1 is a fragmentary elevational view, partly in section, of a hardening machine embodying the invention; and

Fig. 2 is a cross-sectional view taken on the line 2—2 of Fig. 1.

Referring to these drawings, the furnace is indicated in conventional form at 5, and 95 6 is the tubular exit mouth of the furnace. Any suitable type of furnace may be used as desired, and the invention is independent of the specific type of furnace employed. 100 Detailed description and illustration of the furnace are thought unnecessary to an understanding of the invention as furnaces are now well known in the art.

Closely adjacent the exit 6 of the furnace 105 is a tank 7 having a relatively large com-

partment 8 to contain a quenching medium, as oil, and relatively small compartments 9 and 10 at each end thereof. The end wall of tank 7 adjacent the tube 6 is provided 5 with a jacket 11 through which a suitable cooling medium, as water, may be circulated by means of inlet and outlet pipes 12 and 13, respectively, (see Fig. 2). The end walls of tank 7 and the walls dividing compartment 10 8 from the end compartments 9 and 10 are provided with openings 14 in line with tube 6 so that articles 15, as hack-saw blades, connected into chain form by links 16, may be passed in a straight line successively through 15 the furnace 5 and compartments 8, 9, and 10.

The means for supporting, guiding, and propelling the chain of articles 15 have not been illustrated inasmuch as they are unnecessary to an understanding of the invention by those skilled in the art and any suitable supporting, guiding and propelling means may be employed as desired.

Oil is supplied to compartment 8 by an inlet pipe 17 from a suitable source of supply by any suitable means, and the inflow of oil is such as to maintain the surface of the oil a substantial distance above the line of travel of the articles 15. Necessarily, since various sizes of saws are to be handled, 20 the openings 14 cannot readily closely fit any given size of saw, and therefore oil from compartment 8 will flow through openings 14 into the compartments 9 and 10. Such oil as enters the latter compartments may 25 be returned from pipes 18 and 19 to the source of supply, so that no actual loss of oil results and an advantageous circulation of oil in compartment 8 is obtained.

The oil level in compartment 8 is maintained at such a level that the heated saws 30 plunge into the oil at such a depth below the surface that flashing of the oil does not readily occur. As to the ignition of such oil as enters into compartment 9, the jacket 11 35 is provided. This cooling jacket keeps the compartment 9 relatively cool, while otherwise it would be heated to a considerable degree since it is practically contiguous to the exit tube 6, which becomes red hot while the 40 furnace is in operation. Without the jacket 11, therefore, the oil entering compartment 9 would strike a highly heated surface and would frequently ignite and cause a possible conflagration by igniting the large body of 45 oil in compartment 8. The jacket 11 obviates this difficulty inasmuch as it keeps the compartment 9 cool and counteracts the effect of the furnace. The oil enters compartment 9 in a relatively small stream from 50 compartment 8, and the volume of this stream is such that the temperature of the oil may be readily lowered by the jacket 11 to a degree sufficient to prevent its ignition.

The chief difficulty encountered heretofore has been not so much from the en-

trance of the saws into the thickest part of the stream as it leaves orifice 14, but rather from the finely divided spray and splash which is thrown up against the saw blades by the oil which strikes and is deflected from the end wall of compartment 9. Heretofore, such oil encountered a highly heated surface and, when deflected from this surface to the red hot saw chain, was, on account of its temperature, quite likely to 75 ignite and cause trouble. With the described arrangement, however, all the oil entering compartment 9 is cooled, and particularly such oil as strikes the wall of jacket 11 is cooled to a considerable degree, 80 and the danger of oil ignition is reduced to a minimum.

The invention has been disclosed in an embodiment at present preferred, for the purposes of illustration, but the scope of the 85 invention is defined by the appended claims rather than by the foregoing description.

What we claim is—

1. In a hardening machine, a heating means and a liquid quenching means 90 through which a chain of articles may be successively passed, a tank associated with the quenching means to receive liquid overflowing from the latter, and a jacketed wall provided for said tank adjacent the exit of 95 the heating means, through which wall a cooling medium may be circulated to cool the quenching liquid in said tank sufficiently to prevent its ignition.

2. In a hardening machine, a heating 100 means and a tank through which a chain of articles may be successively passed in a straight line, a compartment in said tank containing a body of an ignitable quenching liquid, the surface of which is a substantial distance above the path of travel 105 of said chain, an orifice in said compartment to permit the entrance of the chain, a compartment in the tank between the quenching liquid compartment and the exit of the 110 heating means to receive the liquid flowing from the former through its orifice, and means to cool the liquid entering into the second compartment.

3. In a hardening machine, a furnace, a 115 tank, one end of which is closely adjacent the exit end of the furnace, a jacketed wall in said end of the tank through which a cooling medium may be circulated, a compartment in said tank to contain an ignitable quenching liquid spaced from the jacketed end leaving a second compartment, and an orifice provided in the jacketed end and in each wall of the first 120 compartment through which orifices a chain 125 of articles may be passed in a straight line from said furnace at a substantial distance below the level of the liquid in said compartment, all constructed and arranged so that the liquid flowing from the first 130

compartment to the second compartment through the orifice is cooled by the jacketed wall sufficiently to prevent its ignition.

4. In a machine of the character described, a heating means and a quenching means through which a chain of articles may be successively passed, a tank between the heating means and the quenching means to receive the overflow from the latter, that

wall of said tank adjacent to the heating means being hollow and closed to communication with the tank so that a cooling medium may be circulated within said wall to cool the latter independently of the quenching means for the purposes set forth. 15
